UNITED STATES PATENT OFFICE.

ZELIA NUTTALL, OF DRESDEN, GERMANY.

DESIGN FOR A CHAIR.

SPECIFICATION forming part of Design No. 21,849, dated September 6, 1892.

Application filed August 5, 1892. Serial No. 442,282. Term of patent 3½ years.

To all whom it may concern:

Be it known that I, ZELIA NUTTALL, a citizen of the United States, now residing in Dresden, Germany, have invented and produced a new and original Design for Chairs and Similar Articles of Furniture, of which the following is a specification, reference being had to the accompanying drawings.

In said drawings, Figure 1 is a perspective view of a chair-frame, showing my design.

Fig. 2 is a side elevation of the same.

The leading features of my design consist in the peculiar angular configuration given the legs or supports and portions depending from the body and the series of circular configurations applied to the surface of the structure, as shown.

The base of a chair or similar article embodying my present design presents to the eye of the observer a rectangular body portion A,

with depending corner-supports or legs B, the edges of which are notched, forming angular projections b. Between the legs are central depending portions C of angular configuration, as shown, and around the edges of the parts going to form the base is an edging D. From the base, or more properly from the body A, the side pieces E of the back project upwardly and are formed to present an angular contour with edging, as on the base and legs. Within the edging are formed a series of circular ornaments F, extending around the body and up the side pieces of the back.

What I claim is—

The design for a chair herein shown and described.

ZELIA NUTTALL.
